UNITED STATES PATENT OFFICE

LEWIS M. CLEMENT, OF MOUNTAIN LAKES, NEW JERSEY, ASSIGNOR TO BRANDES LABORATORIES, INCORPORATED, OF NEWARK, NEW JERSEY, A CORPORATION OF NEW JERSEY

DESIGN FOR A RADIOCABINET

Application filed July 11, 1929. Serial No. 32,004. Term of patent 7 years.

To all whom it may concern:

Be it known that I, LEWIS M. CLEMENT, a citizen of the United States, residing at Mountain Lakes, in the county of Morris and State of New Jersey, have invented a new, original, and ornamental Design for a Radiocabinet, of which the following is a specification, reference being had to the accompanying drawings, forming part thereof.

Figure 1 of the drawings is a front view of a radiocabinet; and

Fig. 2 is a side view of a radiocabinet, showing my new design.

I claim:

The ornamental design for a radiocabinet, as shown.

In witness whereof, I have hereunto subscribed my name this 1st day of July A. D., 1929.

LEWIS M. CLEMENT.
